ROTATABL E BOOK REST

Palmerino C. La Falce, 99 17th St., Buffalo, N.Y.

Filed Mar. 4, 1963, Ser. No. 73,801

Term of patent 14 years

(Cl. D33—3)

FIGURE 1 is a perspective view of the rotatable book rest showing my new design;

FIGURE 2 is a front elevational view thereof; and

FIGURE 3 is an enlarged plan view of the rotatable book rest shown in FIGURE 1.

The dotted lines of FIGURE 2 are for illustrative purposes only.

I claim:

The ornamental design for a rotatable book rest, as shown and described.
